CLAIM

The ornamental design for a bottle rack, as shown and described.

DESCRIPTION

FIG. 1 is a top perspective view of a bottle rack showing the new design;

FIG. 2 is a bottom perspective view thereof;

FIG. 3 is a top view thereof;

FIG. 4 is a left side view thereof;

FIG. 5 is a front view thereof;

FIG. 6 is a perspective cross-section view thereof;

FIG. 7 is a further perspective cross-section view thereof;

FIG. 8 is a left side cross-section view thereof along the line shown in FIG. 3;

FIG. 9 is a left side cross-section view thereof along the line shown in FIG. 3; and,

FIG. 10 is a left side cross-section view thereof along the line shown in FIG. 3.

The broken lines showing selected portions of the bottle rack are for environmental purposes only and form no part of the claimed design.
